DRY-SHAVING DEVICE

Leopold Wimberger, Vienna, Austria, assignor to
 L. Wimberger Kommanditgesellschaft & Co.,
 Patent-Verwertungsgesellschaft, Vienna, Austria

Application December 31, 1937, Serial No. 182,871
 In Austria December 10, 1937

10 Claims. (Cl. 30—43)

The invention relates to a preferably electrically operated dry shaver, consisting of an outer shear-plate and an inner shear-member cooperating with the outer shear-plate, the outer shear-plate having in its middle part a plurality of openings of about the same diameter in all directions and, on both side parts, rows of cross-slots and the inner shear-member having a plate-like surface pressed to the inner surface of the outer shear-plate and having also cross-slots, whereby openings of the above mentioned form may also be provided.

One object of the invention consists in that at least a part of the cross-slots at least of the outer shear-plate, moving on the skin, are united with at least a part of the above mentioned, preferably circular openings, the diameter of these openings being greater than the width of the cross-slots. The inner ends of the cross-slots are thus provided with circular enlargements.

As a further object of the invention the inner shear-member is provided with longitudinal bridges by which are connected the cross bridges separating the cross-slots.

By way of examples several forms of the invention are illustrated in the drawing. Figs. 1, 3, 5 and 6 are plan views, illustrating the surface of the outer shear-plate; Fig. 2 is a plan view of the surface of the inner shear-member; Figs. 4 and 7 are cross-sections of the upper part respectively of a detail of the shear-head.

In all figures 1 designates the outer shear-plate and 2 the inner shear-member. Openings 4 of preferably circular form are provided in the middle part of the outer shear-plate 1; on both sides of this plate are provided short cross-slots 3, operating as guiding members for the hairs and as primary shearers. These cross-slots 3 extend directly to the openings 4, the diameter 7 of which is greater than the width 5 of the cross-slots. Each of said cross-slots thus has a circular enlargement at the inner end. The effect of the cross-slots may be improved by tapering the free ends 10 of the same (see Fig. 3). Hairs lying on the skin may be, with greater effect, introduced in the cross-slots by a step-like portion 13 (Fig. 4 or 7).

As a result of the union of the cross-slots 3 with at least a part of the circular openings 4 the hairs entered through the slots 3 in the openings 4 may not escape; therefore an excellent shaving effect is obtained. Hairs not entered in the slots may be caught by the inner openings 4 separated from the slots 3 and provided more in the middle of the plate, preferably for the pur-

pose of a secondary finest shaving. Conforming to the fact, that the outer openings 4 are preferably displaced with respect to one another two unequal lengths of the cross-slots 3 are obtained.

The inner shear-member 2 moved to and fro in relation to the outer shear-plate 1 has preferably slots of a width 8 of greater or the same largeness as the width 6 of the bridges of the shear-plate 1, whereby, conforming to the invention, the cross-slots 3' of the inner shear-member 2 10 being divided in the middle part by small bridges 9. The bridges 9 are staggered, as shown by Fig. 2, and are so located that in one of the end positions of the inner shear-member 2 they are situated between two openings 4 of the shear-plate 15 1. The openings 4' of the inner shear-member 2, if provided in the same, (see left half of Fig. 2) are situated preferably in line with the cross-bridges separating the cross-slots 3'.

During the shaving operation the openings 4 of the outer shear-plate 1 cooperating with cross bridges or openings of the inner shear-member 2 produce a better result of shaving than by known devices, because the cooperating shear-openings 4, 4' in the outer and inner shear-plates are reduced by the movement of the inner shear-plate from the full circular form down to a point.

The cross section of the shearing head illustrated by Fig. 4 shows the situation of the longitudinal bridges 9 and the step-like portion 13 30 for better introducing the hairs in the slots. Fig. 7 shows in modification another form of the step-like portion 13.

In Fig. 5 and Fig. 6 other suitable forms of the cross-slots are illustrated. The slots 11 of Fig. 5 35 are situated obliquely to the longitudinal edge of the shear-plate 1. They extend not radially to the circular openings but tangentially. The arrangement described may also be used for cross-slots such as are shown in Figs. 1 and 3. The arrangement conforming to Fig. 6 shows also obliquely situated slots 12 which are curved.

The invention may be reduced to practice in many other forms not described.

Having now described my invention, what I claim is:

1. A dry-shaving device of the mechanically-electrically operated type, consisting of an outer shear-plate and an inner shear-plate cooperating with the outer shear-plate, the outer shear-plate 50 having in its middle part several rows of shear-openings of generally circular form and having on both side parts short cross-slots, at least a part of said cross-slots being united with at least a part of said shear-openings which thus form 55

circular enlargements at the inner ends of the cross-slots.

2. A dry-shaving device of the mechanically-electrically operated type, consisting of an outer shear-plate and an inner shear-plate cooperating with the outer shear-plate, the outer shear-plate having in its middle part several rows of shear-openings of generally circular form and having on both side parts short cross-slots, at least a part of said cross-slots being united with at least a part of said shear-openings, the diameter of said shear openings being greater than the width of said cross-slots, said cross-slots being of unequal lengths, by virtue of which the openings situated in the rows are displaced with respect to one another.

3. A dry-shaving device of the mechanically-electrically operated type, consisting of an outer shear-plate and an inner shear-plate cooperating with the outer shear-plate, the outer shear-plate having in its middle part several rows of shear-openings of generally circular form and having on both side parts short cross-slots, at least a part of said cross-slots being united with at least a part of said shear-openings at their inner ends whereby said shear-openings constitute circular enlargements at the inner ends of said cross-slots, the outer ends of said cross-slots having outwardly diverging portions constituting wedge-shaped enlargements.

4. A dry-shaving device of the mechanically-electrically operated type, consisting of an outer shear-plate and an inner shear-plate cooperating with the outer shear-plate, the outer shear-plate having in its middle part several rows of shear-openings of generally circular form and having on both side parts short cross-slots, at least a part of said cross-slots being united with at least a part of said shear-openings, the diameter of said shear-openings being greater than the width of said cross-slots, said cross-slots being arranged in oblique relation to the longitudinal edges of the shear-plate.

5. A dry-shaving device of the mechanically-electrically operated type, consisting of an outer shear-plate and an inner shear-plate cooperating with the outer shear-plate, the outer shear-plate having in its middle part several rows of shear-openings of generally circular form and, on both side parts, rows of cross-slots, at least a part of these cross-slots being united with at least a part of the above mentioned openings, the diameter of these openings being greater than the width of the cross-slots, the cross-slots being curved.

55 6. A dry-shaving device of the mechanically-electrically operated type, consisting of an outer shear-plate and an inner shear-plate cooperating with the outer shear-plate, the outer shear-plate having in its middle part several rows of shear-openings of generally circular form and, on both side parts, rows of cross-slots, at least a part of these cross-slots being united with at least a part of the above mentioned openings, the

diameter of these openings being greater than the width of the cross-slots, the inner ends of the cross-slots extending tangentially to the openings.

7. A dry-shaving device of the mechanically-electrically operated type, consisting of an outer shear-plate and an inner shear-plate cooperating with the outer shear-plate, the outer shear-plate having in its middle part several rows of circular shear-openings and having on both side parts short cross-slots, at least a part of said cross-slots being united with at least a part of said circular shear-openings, said inner shear-plate having cross-slots divided in their middle part by small bridges.

20 8. A dry-shaving device of the mechanically-electrically operated type, consisting of an outer shear-plate and an inner shear-plate pressed to the inner surface of the outer shear-plate, the outer shear-plate having in its middle part several rows of generally circular shear-openings and having on both side parts short cross-slots, at least a part of said cross-slots being united with at least a part of said circular shear-openings, the inner shear-plate having also cross-slots divided in their middle part by small bridges, said bridges being displaced with respect to one another.

25 9. A dry-shaving device of the mechanically-electrically operated type, consisting of an outer shear-plate and an inner shear-plate pressed to the inner surface of the outer shear-plate, the outer shear-plate having in its middle part several rows of circular shear-openings and having on both side parts short cross-slots, at least a part of said cross-slots being united with at least a part of said circular shear-openings, the inner shear-plate having cross-slots divided in their middle part by small bridges, said bridges being displaced with respect to one another, shear-openings of generally circular form being provided in the inner shear-plate at the inner ends of the cross-slots thereof.

40 10. A dry-shaving device of the mechanically-electrically operated type, consisting of an outer shear-plate and an inner shear-plate cooperating with the outer shear-plate, the outer shear-plate having in its middle part a plurality of openings of about the same diameter in all directions and, on both side parts, rows of cross-slots, at least a part of these cross-slots being united with at least a part of the above mentioned openings, the diameter of these openings being greater than the width of the cross-slots, the inner shear-member having a plate-like surface pressed to the inner surface of the outer shear-plate and having also cross-slots on both side parts, which slots are separated by bridges, the bridges being staggered, generally circular openings being provided in the inner shear-plate at each side of the cross-slots thereof and in line with said bridges.

LEOPOLD WIMBERGER.
